Patented Mar. 24, 1964

197,817

LABEL MAKING TOOL

Ray S. Avery, Bradbury, Calif., assignor to Avery
Adhesive Products, Inc., San Marino, Calif., a
corporation of California

Filed Oct. 8, 1963, Ser. No. 76,902

Term of patent 14 years

(Cl. D64—10)

FIG. 3

FIG. 4

FIG. 5

FIG. 1 is a top plan view of a label making tool showing my new design;

FIG. 2 is a side elevational view thereof, the side opposite thereto being similar in appearance;

FIG. 3 is a bottom plan view;

FIG. 4 is an end elevational view as seen from the left of FIG. 2; and

FIG. 5 is an end elevational view as seen from the right of FIG. 2.

I claim:

The ornamental design for a label making tool, as shown and described.
